UNITED STATES PATENT OFFICE.

WILLIAM E. PEMBLETON, OF WITTENBERG, WISCONSIN.

ELECTRIC TELEPHONE SYSTEM.

SPECIFICATION forming part of Letters Patent No. 697,009, dated April 8, 1902.

Application filed December 24, 1900. Serial No. 40,878. (No model.)

To all whom it may concern:

Be it known that I, WILLIAM E. PEMBLETON, a citizen of the United States, and a resident of Wittenberg, in the county of Shawano and State of Wisconsin, have invented certain new and useful Improvements in Electric Telephone Systems; and I do hereby declare that the following is a full, clear, and exact description thereof.

10 My invention has for its object to eliminate resistance of the coils of call-signal magnetos from the talking-circuit of an electric telephone system, as well as to provide for testing at any of the telephones whether said circuit is in use or idle, and, furthermore, to provide for automatic signaling of the cutting in and cutting out of said telephones, so as to guard against overhearing on the line or at a switchboard, said invention consisting in what is particularly set forth with reference to the accompanying drawings and subsequently claimed.

Figures 1 and 2 of the drawings are diagrams illustrating means for attaining the objects of my invention.

Referring by letter to the drawings, A B C indicate three parallel conductors constituting the line of an electric telephone system embodying my improvements. Between the 30 conductors B C are bridged all the electric bells or their equivalents for signaling calls, said conductors constituting one part of the talking-circuit of the telephone system and conductor A the other part of said circuit.

35 As herein shown, b indicates a switchboard call-signal, and c a line-telephone call-signal, the magneto D of the latter signal being in permanent electric connection with conductor C aforesaid.

40 A movable contact device E of the form herein shown or otherwise, as may be most convenient, is arranged between two contact-points d e, normally clear of both, these points being, respectively, in electrical connection with conductors A B aforesaid. By touching contact E on point d a call will be sent in on conductors A C, and if said contact be put in touch with point e the call will be sent on conductors B C. At the switchboard is shown 45 a call-signal apparatus comprising a magneto D', wired to contact-springs d' e' opposite other contact-springs d'' e'' in electrical con-

nection with conductors B C, said contact-springs being in the path of arms of a reciprocative device E', constituting a circuit-closer. The magneto D' is also shown wired to opposite bow-contacts f' f'', and spring-contacts g g' h h' are arranged to be brought in touch with said bow-contacts, these spring-contacts being normally against stationary 60 stops i on the switchboard. An insulated slide F is shown in Fig. 1, provided with a slot engaged by a guide-pin, this slide being arranged to move either pair of spring-contacts g g' or h h' away from stops i into touch with bow-contacts f' f'', and said spring-contacts are in flexible electric connection with the sleeves G and pins G' of a pair of switchboard-plugs. Hence it will be understood that a call-signal may be made through either 70 of the plugs, according to the adjustment of slide F, this method of signaling being independent of that above specified. Each plug-sleeve G is exteriorly grooved at its forward end to form a head and neck, and said sleeve 75 is insulated from the contact-pin G', engaged therewith, this pin being extended beyond the sleeve-head.

The conductors B C are electrically connected to contacts j j' in opposition to a contact-shoulder k on the usual tilt-hook lever H, upon which to hang the receiver I of a telephone when not in use. Under ordinary circumstances the shoulder k of the tilt-hook lever is held away from the opposing contacts j j' by weight of receiver I in suspended position; but for the purpose hereinafter specified a pivotal latch m is shown arranged to be brought into position to prevent upward swing of said lever when said receiver 90 is detached therefrom. The lever and receiver are in circuit with the secondary of the telephone induction-coil J, the secondary circuit being closed, when said lever is permitted to swing up, and thereby cause touch of 95 its shoulder k with the contacts j j' aforesaid.

A contact-plate K in insulated connection with lever H is opposed by a contact-point m' in circuit with the primary of induction-coil J, the telephone-transmitter L, and local 100 battery M, this circuit being closed when said lever swings up to cause touch of said plate and point.

In a circuit including receiver I and bat-

tery M is a spring contact-blade n, opposed by a contact-point p, electrically connected to conductor B, and by rotation of a ratchet-wheel striker N the blade is actuated to have 5 intermittent momentary contact with the point. By employment of a detent in engagement with the striker, as herein shown, said striker can be rotated in but one direction by which to prevent other than intermittent momentary contact of said blade and point. From the foregoing it will be readily understood that if latch m is positioned, as herein shown, to prevent upward swing of lever H when receiver I is taken off hook and 10 the striker N rotated in the permissible direction to cause intermittent momentary contact of blade n with point p a clicking will be heard in said receiver, due to current from battery M, if the telephone-line is busy, but not otherwise, the clicking being due to interruptions of said current. In other words, if a talking-circuit be closed on the line and lever H held down when receiver I is removed therefrom intermittent clicking, due 15 to rotation of striker N, will be heard in said receiver then cut into the talking-circuit independent of the induction-coil J, this being evident from the direct wiring of said receiver in a circuit with conductor A, battery M, 20 blade n, point p, and conductor B, as is clearly shown in Fig. 1.

At the switchboard of the herein-described telephone system a normally interrupted circuit is shown in connection with conductors A B and including operator's receiver I', a battery M', ratchet-wheel striker N', a pair of striker-opposing spring-blade contacts n' n', and contact-points p' p', these points being normally out of touch with the blades. The 30 striker N' is engaged by a detent to prevent its rotation in other than one direction, and incidental to the rotary movement of said striker there will be intermittent momentary contact of blades n' n' and points p' p' to obtain impulses from battery M', wired in circuit with receiver I' and conductors A B, and thus cause clicking in said receiver if said line is busy, but not otherwise. It is obvious that the means described in connection with the 35 receiver at the switchboard for busy test of the line are virtually the same as those in connection with other receivers on the line for the same purpose, although there are some differences in the matter of detail.

The tilt-hook lever H is shown provided with an upper arm H', having two pairs of acute-angle edge shoulders q q', the under side of the lower shoulders q' being insulated, and arranged in the path of the arm-shoulders 50 are spring-contacts r in circuit with the local battery and an electric call-bell P or other audible electric signal incased in an arm of the transmitter L aforesaid. When the lever H is permitted to swing up and close circuits at K m' and at k j j', the shoulders q q' of its arm H' will successively strike the contacts r to thereby close circuit and cause two 55

operations of the audible signal P to thereby indicate a cutting in of the line-telephone of which said lever constitutes a part; but in cutting out there will only be one operation of said signal, because of the insulation on the under side of the lower pair of arm-shoulders. Hence it will be understood that in case two parties are talking on the line and another party cuts in this cutting in will be automatically signaled and the conversation need not be continued until the third party cuts out, the cutting out being also signaled. Therefore it follows that overhearing cannot 80 secretly occur on said line.

As shown in Fig. 1, the plugs aforesaid may be utilized in connection with switchboard spring-jacks, each of which comprises a contact-thimble Q, opposite pairs of spring-contacts s s', insulated from each other and the thimble, and another pair of spring-contacts t t', insulated from each other, the first of these latter contacts being longer than its companion. Contacts t t' and thimble Q are 85 respectively in electrical connection with conductors A B C, the contacts s being respectively in electrical connection with conductors A B and in the primary circuit of the switchboard-telephone. The contacts s' are 90 in the secondary circuit of said telephone, and the latter is provided with an audible signal P', similar to the one P aforesaid in connection with a line-telephone. The signal P' is shown in the primary circuit of the switchboard-telephone adjacent to transmitter L' thereof, and it is obvious that when a plug-sleeve G is positioned in the thimble Q to have its head spread contacts s' against contacts s the signal-circuit will be closed and 100 parties conversing on the line notified of the cut-in by the switchboard operator; but when the plug-sleeve is moved to bridge contacts t t' the signal-circuit will be broken by the separation of contacts s s', due to the clearance had by the neck of said sleeve. In the last-described position of the plug its sleeve-head has touch against contact t' and its pin G' is in touch with contact t to connect the aforesaid switchboard-telephone with the two 105 talking-circuits of the line. When the plug is withdrawn from a spring-jack, such as has been shown and described, it is evident that succeeding a breaking of the talking-circuits there will be a momentary closing of the circuit by which to signal cut-out, and it is further evident that the switchboard operator 110 cannot cut in or out without signaling the fact, this being to guard against overhearing by said switchboard operator.

In Fig. 2 is shown a transmitter L'', combined with an audible electric signal P'', that sounds when the switchboard-operator cuts in or out, this transmitter and signal and a battery M'' being auxiliary to the operator's transmitter R and another local battery M' in primary circuit with the same. The operator's receiver is in secondary circuit with the single induction-coil J' shown in common

with the two transmitters. These telephone elements and the signal P'' are in electrical connection with the flexible conductors connecting switchboard-plugs in pairs, these 5 plugs being similar to those above specified, and circuits are made and broken by the means hereinafter specified.

A lever S is provided with a lateral contact-arm T , that is normally caught in a spring-clutch u , the branches of which are insulated from each other, and said arm serves as a circuit-closer. A brush comprising parallel spring-contacts $w' x' y'$, insulated from each other, is shown in the path of oscillative contact-arm T , and by means of the electrical connections herein shown touch of said arm with the brush-contacts will result in closing primary and secondary circuits, so that in case the line is in use the parties conversing 15 will hear signal P'' when the switchboard operator is cutting in or out. When arm T is caused to pass out of contact with the brush aforesaid and engage another spring-clutch Z , (the branches of which are insulated from 20 each other,) a circuit is established through operator's receiver, induction-coil J' , and one of the flexible conductors aforesaid, the operator's transmitter R and battery M' being 25 also in circuit with said coil.

30 To prevent the operator from giving the cut-out signal and then swinging arm T to again cut in, a weighted swing-stop U is arranged in the path of said arm to be normally in vertical position, the upper end of this 35 stop being made to form a right-angle notch facing the spring-clutch aforesaid. The arm T being swung from normal position to cut in the operator, the swing-stop U moves out of the way of said arm incidental to pressure thereon; but when the reverse or cut-out operation is performed said arm engages the notch of the stop before coming into touch with the brush by which to close the primary and secondary circuits, and it is required 45 that the aforesaid arm be swung clear of the stop-point and beyond the brush before said stop can have automatic return to its normal position, as is evident from the dotted-line showing herewith. Another pair of 50 switchboard-plugs are shown in Fig. 2 as having their flexible conductors wired in series with those described in connection with the cut-in and cut-out lever S , and another lever S' , provided with a lateral contact-arm T' , has 55 the function of a circuit-closer, its arm being arranged to come in touch with a brush comprising spring-contacts $w' x' y'$ (insulated from each other) and after passing the brush in one direction to engage a spring-clutch Z' , the branches of which are separated by 60 insulation. The brush-contacts and clutch branches last specified are similar in arrangement and connections with the conductors connecting the second pair of plugs, and one 65 of said clutch branches is put in electrical connection with a branch of clutch Z afore-

said. An annular notched and weighted swing-stop U' is arranged in the path of contact-arm T' to prevent a switchboard operator from signaling cut-out and again cutting in 70 without signaling. It also follows that before contact-arm T' can be utilized the other contact-arm T must be in normal position; otherwise it would be possible to cut in with the lever of one set of plugs and signal cut-out with 75 the lever of another set of plugs, and no matter how many sets there may be in series at the switchboard it requires that all the lever-control contact-arms T shall be in normal position before any one of the contact-arms T' 80 can be utilized to cut in.

The showing in Fig. 1 is designed to illustrate a division of my telephone system that may include another division embodying what is shown in Fig. 2, and supposing the 85 switchboard operator at a terminal of the first division receives a call for a telephone in the second division the two divisions are connected by plugging and signals are given, as above described. The operator necessarily remains 90 connected with the plugs in use until parties at connected telephones are ready to converse, and then incidental to cutting out of said operator there is automatic signal to said parties, so that they may know that their conversation 95 is not being overheard by the aforesaid operator. It is also to be understood from the foregoing that no switchboard operator on the line can cut in without signaling the fact to parties that may be at the time in conversation on said line.

Having thus described my invention, what I claim as new, and desire to secure by Letters Patent, is—

1. An electric telephone system having a 105 spring-contact and an opposing contact-point normally separated at each station, a telephone-receiver and a local battery in circuit with said contact and point, a one-way ratchet-wheel operative against the spring-contact, 110 the tilt-hook lever for said receiver, and means for holding the lever in normal position when said receiver is removed therefrom, whereby intermittent momentary interruptions of current from said battery occurring incidental 115 to rotation of said wheel against said spring-contact are then audible in the aforesaid receiver.

2. An electric telephone system having an 120 audible signal at each station thereof arranged to influence a transmitter, and means for actuating the signal simultaneous with the opening and closing of the talking-circuit at the same station, whereby when the signal is made it will be heard in receivers connected 125 on the line.

3. An electric telephone system having an 130 audible electric signal in normally open circuit at each station thereof arranged to influence a transmitter, and means for making and breaking said circuit simultaneous with the closing and opening of the talking-circuit at

the same station, whereby when the signal is made it will be heard in receivers connected on the line.

4. An electric telephone system embodying 5 tilt-hook levers each provided with a shoul- dered arm constituting a circuit make-and- break device, an electric audible-signal de- vice in a local circuit having terminals in the path of said lever-arm and a telephone-trans- 10 mitter arranged to be influenced by the signal device.

5. An electric telephone system including 15 a switchboard, an electric audible-signal de- vice, the transmitter of a switchboard-tele- phone arranged to be influenced by the signal device, and means for energizing said signal device simultaneous with closing and open- 20 ing of talking-circuit at the switchboard, as well as for preventing open signal being given 25 while the talking-circuit is closed at said switchboard.

6. An electric telephone system comprising 25 a switchboard, an electric audible signal at the switchboard in a local circuit electrically connected to the line, a transmitter arranged to be influenced by the signal device, switch-

board-plugs electrically connected in pairs and likewise connected with the signal-cir- 30 circuit, spring-contacts insulated from each other to constitute a brush in said signal-cir- circuit, a contact-arm movable on an arc of a circle to operate as a circuit-closer in conjunc- 35 tion with the brush, and a gravity swing-stop having the upper end thereof arranged in the path of said arm, this end of the stop being 40 made with a right-angle notch facing in a di- rection away from the aforesaid arm when the latter and said stop are in normal position, whereby there is no interference of one with the other on swing of the arm from normal 45 position to pass the brush, but engagement of said arm in the stop-notch preliminary to re- contact with said brush on reverse move- ment.

In testimony that I claim the foregoing I 45 have hereunto set my hand, at Wittenberg, in the county of Shawano and State of Wis- 50 consin, in the presence of two witnesses.

WILLIAM E. PEMBLETON.
